UNITED STATES PATENT OFFICE.

CLARENCE D. FINLEY, OF MEMPHIS, TENNESSEE.

GAS-GENERATOR.

No. 846,295.

Specification of Letters Patent.

Patented March 5, 1907.

Application filed February 21, 1906. Serial No. 302,289.

To all whom it may concern:

Be it known that I, CLARENCE D. FINLEY, a citizen of the United States, residing at Memphis, in the county of Shelby and State 5 of Tennessee, have invented a new and useful Gas-Generator, of which the following is a specification.

The present invention relates to an apparatus for the manufacture of gas for illuminating and heating purposes.

The principal object of the invention is to provide a cheap and simple form of gas-generator which may be used for small plants, such as for domestic purposes, wherein gasolene or other light hydrocarbon is volatilized by the action of heat and conducted directly to the burners.

A further object of the invention is to provide a device of this character in which provision is made for entirely surrounding the gasolene - containing casing with a water-jacket, the water-jacket being heated externally and the heat conveyed to the gasolene-tank through the water.

25 A still further object of the invention is to provide a device of this character in which the water-jacket is surrounded by an external casing for conserving the heat and exposing the greater portion of the outer surface of 30 the water-jacket to the action of the products of combustion.

With these and other objects in view, as will more fully hereinafter appear, the invention consists in the novel construction and 35 arrangement of parts hereinafter fully described, illustrated in the accompanying drawings, and particularly pointed out in the appended claim, it being understood that various changes in the form, proportions, 40 size, and minor details of the structure may be made without departing from the spirit or sacrificing any of the advantages of the invention.

In the accompanying drawings there is 45 shown in sectional elevation a gas-generating apparatus constructed in accordance with the invention.

The central tank 1 is preferably cylindrical in form and has a conoidal top, from the 50 upper end of which leads a gas-outlet 2, and said tank is provided with a filling-pipe 3, through which the liquid gasolene or other

hydrocarbon may be introduced, the top of said pipe being closed by a removable cap 4.

The gasolene-tank is entirely surrounded by a water-jacket 5, into which water may be admitted through a supply-pipe 6, the water being maintained at the level indicated by means of a float-valve 7 of any ordinary construction, and at a point above the water-line the jacket is provided with a petcock 8, through which the steam may be discharged from time to time in order to avoid danger of explosion.

Surrounding the water-jacket to a point at least up to the water-line is a heat-conserving casing or jacket 9, the lower central portion of which has an opening 10, which may be placed directly above the lamp or gas-jet for the purpose of heating the water in the jacket 5.

As a matter of convenience the outer jacket is provided with standards 11, and the heating device in the present instance is shown as comprising a burner 12, that is connected to the gas-outlet pipe 2, so that the apparatus is kept in operation by its own gas. When starting, it will of course be necessary to use some separate source of heat.

In the operation of the device the heat of the outer jacket 5 is absorbed by the water and conducted to the gasolene-tank 1, the temperature being sufficiently high to volatilize the gasolene or other light hydrocarbon. The vapor is driven off through the pipe 2 to the point of consumption, but no air is mingled with the gas or vapor until the burner is reached, so that danger of explosion at the generating-tank is reduced to a minimum.

Having thus described the invention, what is claimed is—

A domestic gas-generator comprising a pair of closed chambers, each having a conoidal top, and one being entirely inclosed within the other and having its walls spaced at substantially equal distances from the other at all points, the innermost chamber serving for the reception of hydrocarbon, a hydrocarbon-inlet, and a gas-outlet connected to the top of the inner chamber, the outer chamber serving as a water-jacket and the upper portion thereof forming a steam-space, a secondary jacket or casing surrounding the water-space of the outer chamber and having a closed top, and means for main-

taining the water-level of the outer chamber in approximately the horizontal plane of the closed top of the outer jacket, the bottom of said outer jacket being provided with an opening for the admission of a heating medium, and supporting-legs on which said outer jacket is mounted.

In testimony that I claim the foregoing as my own I have hereto affixed my signature in the presence of two witnesses.

CLARENCE D. FINLEY.
